CLAIM

The ornamental design for a medical diagnostic positioner for diagnostic imaging or tomography, as shown and described.

DESCRIPTION

FIG. 1 is a perspective view of a medical diagnostic positioner for diagnostic imaging or tomography, showing our new design;

FIG. 2 is a front elevational view thereof;

FIG. 3 is a rear elevational view thereof;

FIG. 4 is a top plan view thereof; and

FIG. 5 is a side elevational view thereof.

FIG-1

FIG-2

FIG-3

FIG-4

FIG-5
